Primary Examiner — Susan Moon Lee(74) *Attorney, Agent, or Firm* — Flynn, Thiel, Boutell & Tanis, P.C.(57) **CLAIM**

The ornamental design for an SD memory card, as shown and described.

DESCRIPTION

FIG. 1 is a top front perspective view of an SD memory card showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Broken lines and unshaded portions contained within broken lines are not claimed.

1 Claim, 4 Drawing Sheets(56)
